Primary Examiner—Robert A. Delehanty*(74) Attorney, Agent, or Firm*—McAndrews, Held & Malloy**CLAIM**

The ornamental design for the recessed shower receptacle, as shown and described.

DESCRIPTION

FIG. 1 is a perspective view of the invention showing the lid closed, and illustrating details of the receptacles.

FIG. 2 is a perspective view of the invention showing the lid open, and illustrating details of the receptacles.

FIG. 3 is a top plan view of the invention, showing the lid open and showing further details of the webs forming the side wall apertures.

FIG. 4 is a side elevation of the invention; and, FIG. 5 is a bottom plan view of the invention.

The broken line showing in FIG. 3 of the drawing views is for illustrative purposes only and forms no part of the claimed design.
